ADJUSTABLE BAR, FRAME THRESHER
SCREEN

William A. Holtzman, Peoria, Ill., assignor to
Hart-Carter Company, Peoria, Ill., a corpora-
tion of Delaware

Application May 21, 1942, Serial No. 443,919

4 Claims. (Cl. 209—394)

1

This is a continuation-in-part of my copending application Serial No. 416,036, filed October 22, 1941 for Steel frame thresher screen.

This invention relates to thresher screens such as are employed in grain threshers or combined harvester threshers.

Heretofore the frames of such screens have been commonly made of wood because this material, when of good quality, made a satisfactory frame for ordinary uses and could be readily repaired in the field by ordinary tools in the hands of farm mechanics. However, the growing use of combined harvester threshers with greatly increased harvester speeds and the stresses and strain of rapid transportation over rough ground, together with increased difficulties in getting proper quality lumber for frames, has indicated the need for stronger, stiffer and better-fitting thresher screens.

The particular object of this invention is to provide a structure for steel frame thresher screens which is strong and light and may be made up in a wide variety of accurate sizes from the same tools and which may be quickly and easily repaired by farm mechanics with ordinary tools.

Another object is to provide adjustment mechanism for steel frame screens which may be mounted within the frames but independent of the frames and without the necessity of any additional pivot holes in the frames.

Other objects and benefits will be disclosed in the following descriptions and drawings, in which:

Fig. 1 is a top plan view showing my new steel frame thresher screen;

Fig. 2 is a cross sectional, elevational view through an end section frame, as it would appear on the section lines 2—2 of Fig. 1;

Fig. 3 is another similar cross sectional view as it would appear on the section lines 3—3 of Fig. 1;

Fig. 4 is an enlarged perspective view of a steel reinforcement member, as will later be explained;

Fig. 5 is a broken, cross sectional, elevational view of the side frame showing the cross wires mounted in support notches, as would appear on the section line 5—5 of Fig. 1;

Fig. 6 is a broken side elevational view, partly in section, showing the center frame member and its mounting on the end members of the frame;

Fig. 7 is an end sectional elevational view of the center member showing a cross wire with

2

adjustment crank, as would appear on the section line 7—7 of Fig. 1;

Fig. 8 is a broken underneath plan view of the frame corner with partial assembly shown in dotted outline, as will later be explained;

5 Fig. 9 is an upright section of the frame corner, as would appear on the line 9—9 of Fig. 8;

Fig. 10 is a developed plan view of the end frame member, later to be explained;

10 Fig. 11 is an enlarged broken side elevational view showing the screen adjustment device;

Fig. 12 is a bottom plan view of the broken section shown in Fig. 11;

15 Fig. 13 is a cross sectional and elevational view showing the adjustment mechanism as it appears on the section line 13—13 of Fig. 11;

Fig. 14 is an enlarged fragmentary end elevational view showing an alternative form of central rail and adjustment device;

20 Fig. 15 is a bottom plan view of the fragmentary section shown in Fig. 14;

Fig. 16 is a fragmentary part sectional and part elevational view of the adjustment mechanism taken in a plane represented by line 16—16 in Fig. 14 of the drawings;

25 Fig. 17 is a fragmentary perspective view of an end portion of part of the alternative form of central rail; and

30 Fig. 18 is a fragmentary part sectional and part elevational view of an alternative form of central rail.

Now referring to the drawings, I designate the side rails of the thresher screen by the numeral 15. The end rails 16 are attached to the side rails with a corner reinforcement member 17, as will later be explained in greater detail.

Referring to Figs. 2 and 3, it will be observed that the end rail 16 is made in a general rectangular tubular section with top extending flanges 16a and 16b extending inwardly therefrom. It will be understood that the rails 15 are made in similar section, having inwardly extending flanges 15a and 15b. However, the side rails 15 have circular indentations 15n embossed downwardly in the top of the flanges 15a and 15b to form pivot sockets for the slat wires 18, as clearly shown. Any suitable means, such as a plate 15c, may be held over these sockets by suitable securing means to prevent the ends of the wires 18 from being displaced therefrom under normal operating conditions. Extending crosswise in the center of the frame is a central rail made up of two sections 20 and 21, which 50 may be of wood, metal, or any other suitable

material joined together by any suitable securing element 22, such as screws, bolts or the like, as clearly shown in Fig. 7. This central rail is fastened to the frame by rivets 23 extending through the sections 16a and 16b of the end rails, as clearly shown in Fig. 6. It will be appreciated that these rivets 23 hold merely the bottom member 21, and the top section 20 may be removed with any suitable tool by removing the securing element 22, whereupon the cross wires 18, having central cranks 18c, may be removed for repairs or replacements of the slats 19.

The adjustment mechanism for the sieve slats will be explained later in connection with Figs. 11, 12, and 13.

Referring to Figs. 4, 8, 9 and 10, it will be observed that the steel corner reinforcement member 17 is made with square corners in accurate square conformation. This reinforcement section is inserted in the hollow corner and, as will be observed by a study of Figs. 4, 8, 9 and 10, the square corner section permits the rails 15 and 16 to be assembled with accurate square corners and with the holes 16h and 16i in alignment where they may be securely held by the through rivets 24r. It will be observed that the ends of the rails 15 and 16 are arranged to abut and overlap each other to effect a stiff, interlocked corner. I show in Fig. 10 the flat, developed plan view of the end rails 16, and I wish to explain that the entire end of the rails 16, including the hole 16i, is cut with a die to effect accurate corner configuration of the rail. The side rails 15 have square ends and therefore the hole 16h, only, is punched in accurate relationship with the square ends. By observing Figs. 8, 9 and 10 it will be seen how the rails are interconnected with the flat section 16f of the rail 16 extended as shown in dotted outline in Figs. 8 and 9. When assembled and riveted in accurate position the section 16f is folded over, and the entire assembly spot-welded together, as indicated at spots marked W, Fig. 8.

An analysis of this structure will show that the stiffener members 17 contribute largely to the stiffness of the assembly because they are inserted at the point of greatest strain, namely the corners.

However, in some installations, particularly with small screens, the stiffener member 17 may be left out, thus sacrificing strength for lightness.

It will be further observed that my rails are formed by bending operations which may be performed with any length of rail desired. Therefore, in order to make different size screens it is necessary to adjust only the length of the rails, and thus screens of various sizes may be constructed with the same set of tools.

It will also be observed that the cross wire indentations 15n and the side rails effectively prevent shifting of the extended flanges 15a and 15b, especially when these flanges are spot-welded together. Inwardly extending flanges 15a-15b and 16a-16b are important elements in my novel structure because they permit not only effective fastening together of the rails and the mounting of the cross wires 18 of the slats 19, but by their very nature permit field repairs with ordinary tools in the hands of a farm mechanic.

It will be appreciated that in high-speed, combined harvester threshers, the screens must fit accurately and firmly in position in order to effectively utilize the air blast and withstand severe service strains.

Now referring to Figs. 11, 12 and 13, I will de-

5

scribe my slat adjustment mechanism which is mounted entirely on the center rail 21. Into the cranks 18c of the cross wires 18 I mount the adjustment rack 24 by means of the spaced slots 24s. The rack 24 is welded to a control arm 25 by a butt weld 24w and the control arm 25 is held in adjustable position by the slot plate 26, fixed to the rail 21 by screws 27. The fastening is made by a thumb bolt 28 through the slots 26s. The extended down-curved end 25h serves as a handle to move the rack 24 to any desired adjustment of the slats.

Referring to Figs. 14, 15, 16 and 17 and 18, showing alternative forms of central rails and slat adjustment mechanisms, the central rail may comprise an angle bar 20a, of metal or the like, to which is suitably secured, as by screws, bolts, or the like, a bar 20b (Fig. 16) which may be of wood, composition, or the like, or an angle bar 20c (Fig. 18) which may be of metal, or other materials. Each end of the bar 20a has a laterally bent ear 20d provided with a suitable aperture 29 for the reception of a securing element, such as a bolt 20e, for fastening the bar 20a to the end rails 16 (see Figs. 14 and 15).

The lower or depending portion of the bar 20a is provided with slots 20h through which extend and in which rotate the wires 18. As in the other forms these wires have cranks 18c carrying the adjustable racks 24. These depending portions of the bars 20a also have apertures 20g for the passage of bolts or the like 20f which act as detachable securing means for lower bars 30 extending along the lower portions of the bars 20a. The upper edge of each bar 30 has slots 30a to act as bearings for the wires 18 adjacent the slots 20h.

To the lower edge of the bar 30 is secured, as by welding 31 (see Fig. 16) an angle bracket 32, the horizontal arm of which carries a pivot stud 33 which may be tightened into clamping condition by a thumb nut 34. Pivotedly mounted on this stud 33 is a control arm 35 which may be angularly adjusted about the axis of the stud 33 and held in adjusted position by tightening the thumb nut 34. This control arm 35 corresponds to the control arm 25 in the form of the device shown and described.

To the side of the adjustable bar or rack 24 is secured, as by rivets 36, an angle bracket 37 located opposite the angle bracket 32, and having its lower arm extending in an opposite direction from the lower arm of the angle bracket 32 for a purpose later explained. The lower arm of the bracket 37 has secured to it a pivot stud 38 having its shank 39 extending downward through a slot 40 provided in the control arm 35 (see Fig. 15).

To adjust the rack 24, and hence the wires 18, the thumb nut 34 is loosened and the control arm 35 swung to the desired position, such as to that shown in Fig. 15, and the thumb nut then tightened to clamp the control arm 35 into adjusted position. In adjusting when the arm 35 is swung it moves the stub 39 and the bracket 37 to which it is secured, and hence the rack bar 24 to which the bracket 37 is secured.

The above structure is designed to be easily and simply assembled and disassembled. Whenever it is desired to make a repair, as by replacing a wire 18 which may have become broken or otherwise damaged, the bolts 20e are removed to detach the bar 20a therefrom, and the bolts 20e are also removed to detach the bar 20a-20b or 20a-20c therefrom. The latter is then raised

from the assembly, thus freeing the wires 18. The wire 18 to be removed is then lifted out and another put in its place, and the parts removed then easily bolted back in place.

Since the ends of the wires 18 in their bearing sockets 15n are preferably covered by the retaining plates 15c, to remove a wire, as above mentioned, it is only necessary to slightly upwardly bow the intermediate portion of the wire whereat the ends of the wire slip out axially from its bearing sockets 15n. The same process is used conversely to insert a new wire.

I claim:

1. In a thresher screen having side and end rails formed in hollow rectangular sections with inwardly extending flanges, pivot sockets embossed in the flanges of the side rails, pivotally adjustable cross wires having adjustment cranks and mounted in the sockets, sieve slats mounted on the wires, a rail removably mounted on the frame for holding the cross wires and slats in operative position and for permitting their removal for replacement and repairs, an adjustment rack mounted in the cranks of the cross wires, a control arm connected to the rack, and adjustable anchor means mounted on the removable rail to hold the rack and slats in adjusted position, the arrangement providing adjustment mechanisms mounted on the removable rail independent of the frame to permit removal of the slats for replacement and repairs.

2. In a thresher screen having side and end rails formed in hollow rectangular sections with inwardly extending flanges, pivot sockets embossed in the flanges of the side rails, pivotally adjustable cross wires having adjustment cranks and mounted in the sockets, sieve slats mounted on the wires, a rail removably mounted on the frame for holding the cross wires and slats in operative position and for permitting their removal for replacement and repairs, a slat adjustment mechanism mounted on the removable rail, the arrangement providing adjustment mechanism mounted entirely on the removable rail and independent of the frame to permit removal of the slats for replacement and repairs.

3. In a thresher screen having side and end rails, pivotally adjustable cross wires having adjustment cranks and mounted on the side rails,

sieve slats mounted on the wires, an intermediate rail mounted on the end rails for holding the cross wires and slats in operative position, an adjustment rack mounted in the cranks of the cross wires, a control arm connected with the rack, and adjustable anchor means mounted on the intermediate rail for holding the rack and slats in adjusted positions, said intermediate rail including upper and lower sections with said upper section projecting at the ends thereof over the end rails and detachably connected therewith and forming the sole support for the intermediate rail on the end rails, whereby upon detachment of said end connections, the intermediate rail and wires are removable as a unit from the side and end rails for replacement and repairs.

4. In a thresher screen having side and end rails, cross wires pivotally mounted on the side rails, sieve slats mounted on the wires, an intermediate rail mounted on the end rails for holding the cross wires and slats in operative position, slat adjusting mechanism connected with the wires and mounted on the intermediate rail, said intermediate rail including upper and lower sections with one of said sections projecting at the ends thereof in overlapping relation with the end rails and detachably connected therewith and forming the sole support for the intermediate rail on the end rails, whereby upon detachment of said end connections the intermediate rail and wires are removable as a unit from the side and end rails for replacement and repairs.

WILLIAM A. HOLTZMAN.
